UNITED STATES PATENT OFFICE.

LOUIS BROUSSAS, OF LYONS, FRANCE.

PROCESS OF CONNECTING T-IRONS.

SPECIFICATION forming part of Letters Patent No. 650,299, dated May 22, 1900.

Application filed May 9, 1898. Serial No. 680,203. (No model.)

To all whom it may concern:

Be it known that I, LOUIS BROUSSAS, a citizen of the Republic of France, residing at Lyons, France, have invented certain new and useful Improvements in Building Structures, of which the following is a specification.

This invention relates to materials designed particularly for building or erecting bridges, but useful also in the manufacture of columns, beams or girders, and other objects.

The chief object of my invention is to provide a new and improved building structure possessing such characteristics that while composed of cement or agglomerant and iron parts it is strong, substantial, durable, and capable of successfully resisting excessive shocks, pressures, and strains. This object is accomplished in the manner and by the means hereinafter described and claimed, reference being made to the accompanying drawings, in which—

Figure 1 is a view, partly in elevation and partly in section, of a post constructed in accordance with my invention. Fig. 2 represents a horizontal section through the same post, showing the arrangement of the T-irons. Figs. 3 and 4 each illustrate a different means of connecting at intervals the T-irons one with the other. Figs. 5, 6, 7, and 8 show different forms of posts or pillars and also the devices for connecting the T-irons one with the other which may be employed according to various applications of my invention. Figs. 9 and 10 illustrate the application of my invention to a factory chimney-shaft. Fig. 11 shows the invention applied to the principal rafters of trusses and to columns. Figs. 12 and 13 represent the application of the invention to a concrete tile or slab for roofing.

Similar letters of reference indicate corresponding parts in all the figures of the drawings.

As shown in Figs. 1 and 2, a post or column constructed in accordance with my invention consists of four T-irons A A A A, serving as an external casing or protection and forming flattened angles, the webs or flanges of such T-irons being embedded in the cast mass or agglomerant substance B. These T-irons A, which at the same time serve to protect the posts against shocks, are connected one with

the other at intervals by their flange either by means of iron wires C C, which are bent at their extremities, or by means of small bands of stamped iron, which serve the same purpose. In order to facilitate the assembling of these irons A to insure their being separated by exactly similar intervals previous to their connection and also in order to impart a still greater degree of cohesion to the mass, a series of plates D, (see Fig. 3,) having their angles cut out so as to form a bearing for the flanges of the T-irons, may advantageously be arranged at intervals in the pillar or column. In pillars of large section the plates D may be replaced (see Fig. 4) by a series of cross-pieces E with notched extremities and serving to connect the T-irons one with the other with great rigidity.

When the T-irons have been arranged in the desired positions, according to the size of the pillar or column to be constantly and rigidly connected one with the other, the agglomerant substance is cast directly within them and consolidated in the usual manner while temporarily retained by means of boards, planks, a frame, or the like, forming a mold and imparting the desired configuration to the object constructed.

If the posts are intended for use for telegraphic lines, for example, they may be cast with their insulating substance direct. To the top of these posts may be applied any desired ornamentation—of the kind illustrated in Fig. 1, for example. They may likewise receive the collars or supports necessary for the applications for which they are intended. Instead of being made solid these posts may equally well be cast hollow, as shown in Figs. 5, 6, 7, and 8. In this case the flanges of the T-irons instead of being united diagonally by the iron bands or wires C are connected directly with the flanges adjacent to them, either with or without the use of iron frames F, (see Fig. 6,) fulfilling the office of the plates D and of the cross-pieces E. The frames F are arranged at intervals along the post and connected with the T-irons by means of iron wires or hooks, insuring efficient fixing.

In accordance with my invention either solid or hollow columns may be constructed (see Fig. 7) of any desired form and ornamented by flutings between the irons, for ex-

ample. Also pillars may be constructed (see Fig. 8) of any desired form, solid or hollow, and comprising in this latter case a second and internal casing E', consisting of other T-irons reinforcing the T-irons of the external casing A. These two series of irons (the internal and external) are rigidly connected at intervals one with the other in the manner already described and also with the irons A as a whole by means of iron wires or connections C and suitable bearing-frames F. In order to give still greater rigidity to the pillar, these two series of single T-irons may be replaced by a single series of double T-irons connected one with the other in the manner above described.

Factory chimney-shafts may also be constructed in accordance with my invention in the manner illustrated in Figs. 9 and 10, for example, either by means of a cast agglomerant substance or of bricks. In this application to chimney-shafts the frames F are replaced by notched or indented iron hoops G, (see Fig. 10,) which being engaged and connected with each of the flanges of the T-irons and being embedded in the mass at intervals impart complete cohesion to the whole.

This invention may likewise be advantageously applied to the construction of trusses with columns and of tile roofing in accordance with my invention, as represented in Fig. 11. In order to form the rafters, the agglomerant substance is cast in a frame formed by two lengths of T-irons, the upper of which, the length H, being straight, while the lower, H', may form a curve varying according to the pitch of the rafter. The extremities of this lower length H' are turned up to facilitate its connection with the upper length H. A certain number of connections C unite the lengths H and H' one with the other in the manner already described. As regards the columns to which these rafters are attached they are likewise formed of an agglomerant substance cast between the two T-irons. M M. and are connected with the rafters by means of fish-plates or cheeks N. The rafters are connected one with the other at the ridge of the roof by means of other fish-plates I. Finally, the roofing consists of slabs or tiles, which are also formed by cast-

ing the desired agglomerant substance in an iron frame, (see Figs. 12 and 13,) two opposite sides of which are formed by small T-irons A A, the other two opposite sides consisting of angle-irons P P. In order to impart a greater degree of consistency to the slab, a bar O, which is fixed at both extremities to the angle-irons, is embedded in the thickness of the plate and likewise serves as an intermediate connection between the iron wires C.

The T-irons above referred to may be employed either in the rough or nickeled, 65 bronzed, or galvanized. They may also be of the ordinary form or slightly molded or fluted in order to produce a more decorative effect.

Finally, my invention is equally capable of application to a multiplicity of other purposes—such, for example, as the construction of the arch-stones or voussoirs of bridges, the coping of walls, timber summers, conduit-pipes, vats, reservoirs, gasometers, the spires 75 of edifices, &c.

It will be observed that in the different forms of my invention the T-shaped irons or columns have their faces presented outward and their webs projecting inward, all being 80 embedded in the plastic or agglomerant substance. This arrangement of the T-shaped irons or columns enables the structure to successfully resist or withstand excessive shocks and pressures.

What I claim is—

A building structure, consisting of a mass of plastic material or agglomerant, a plurality of T-shaped irons spaced apart, embedded in the plastic mass or agglomerant and having their faces presented outward and their webs projecting inward, and tie-wires connecting the inwardly-projecting webs of the T-shaped irons and also embedded in the plastic mass or agglomerant, substantially as 95 and for the purpose described.

In testimony whereof I have hereunto set my hand, in presence of two subscribing witnesses, this 28th day of April, 1898.

LOUIS BROUSSAS.
